BENJAMIN ADRIANCE AND AMOS CALLESON, OF BROOKLYN, NEW YORK, SAID
CALLESON ASSIGNEE TO SAID ADRIANCE.

METHOD OF MAKING BOTTLE-CAPS.

1,002,354.

Specification of Letters Patent. Patented Sept. 5, 1911.

Application filed December 14, 1910. Serial No. 597,194.

To all whom it may concern:

Be it known that we, BENJAMIN ADRIANCE and AMOS CALLESON, citizens of the United States, residing in Brooklyn, and State of New York, have invented certain new and useful Improvements in Methods of Making Bottle-Caps; and we do hereby declare the following to be a full, clear, and exact description of the invention, such as will enable others skilled in the art to which it appertains to make and use the same, reference being had to the accompanying drawing, and to letters of reference marked thereon, which forms a part of this specification.

This invention relates to flanged caps for bottles and the like having sealing disks of cork or similar substances; the common method of securing the disks in the flanged shells of the caps, *i. e.*, by the employment of adhesion in one way or another operating as between the top surface of the disk and the under surface of the top wall of the shell, is objectionable for various reasons known to those familiar with the art and among which may be mentioned the failure frequently to secure a regular intimate binding between all parts of said surfaces, so that undesirable spaces are formed between them, and in many instances the failure to secure any binding together of said surfaces whatever, so that the disks fall out and make the product commercially useless.

In accordance with the present invention resort to adhesion is not necessary, and a crown or cap is produced in which the securing of the disk in the shell is accomplished in a novel way involving displacement of the shell flange inwardly toward the central or the vertical axis of the shell from different radial directions simultaneously and into permanent overlying relation to the margin of the disk, to wit by forcing the flange inwardly upon a moment of bending lying within the zone or annular part of the shell where its top wall and flange merge together and preferably until the exposed surface portion of the already-introduced sealing disk is by the shell-flange subjected to a condition of greater transverse compression or density than the remainder thereof, whereby the further advantage accrues that the disk tends to arch toward the top wall of the shell, sealing any interstices which otherwise might remain to allow

leakage of the pressure from the container to which the finished closure becomes attached. A further advantage of this method is the great saving of time, labor and material clearly resulting.

In the accompanying drawing, Figures 1, 2 and 3 shew a so-called "crown", in side elevation, plan and transverse section, produced by the present method; Fig. 4 shows the sealing disk in plan and side elevation; and, Figs. 5 and 6 illustrate two steps of the said method.

The cap shown in Figs. 1, 2 and 3 of said drawing comprises the shell *a* and disk *b*. The shell has the top wall *c* thereof and depending flange *d* formed in the usual manner, the flange being in the present instance fluted or corrugated for the purpose of securing its interlocked engagement with the shoulder on a bottle. The disk *b* is formed of cork, though any substance suitable for securing a hermetic closing of a bottle or the like may be employed, cork in the present instance being preferred because it possesses the qualities of compressibility and flexibility. The shell-flange in a plane below the top surface plane of the disk possesses a less dimension between opposing inbends *f* of its corrugation than the corresponding dimension of the top surface of the disk (Fig. 3); an inwardly projecting portion, obstructing the removal of the disk, is thus formed in the flange, being afforded in the present instance by each of the inbends *f*. The disk is thus held in the shell because the shell flange affords obstruction to its removal. In addition, however, a compressing influence is exerted by the shell-flange on the disk crosswise of the latter and maintaining its exposed surface-portion in a state of greater density than the remainder thereof; this is due to the fact that certain dimensions of the disk in its normal condition and crosswise thereof and in its exposed surface-portion, that is to say, before being inserted into the shell, are greater than when the disk occupies the shell, because then the shell-flange holds the disk in a state of contraction.

The cap shown in the drawing is formed as follows: The disk is first introduced into the shell. The assembled parts, standing in opposed relation to an opening or other form of passage *g* provided in the bending implement *h*, which passage is

of such a diameter that the shell cannot pass through it without undergoing contraction, are then forced by the plunger *i* toward and through the passage, with the result that the marginal portion of the shell (in the present instance, its flange *d*, which may have the flaring form shown, initially) is contracted, each part thereof moving lever-fashion inwardly about a line of bending coinciding with an annular line surrounding the vertical axis of the shell and itself preferably coinciding with the plane (*x-x*, Fig. 5) where the top and side walls of the shell merge until the flange grips the disk and more or less compresses the latter crosswise thereof as above stated. This compressing action operates principally in the present instance on the lower or outer face portion of the disk more than, or relatively to, the upper portion of the disk, whereby the density of the disk in said portion is made to be greater than that in the portion of the disk above the same, so that the disk tends to arch and its top surface is caused to assume intimate contact with the top wall of the shell and close any space or spaces that might otherwise exist. The dotted line *k* in Figs. 5 and 6 shows how this arching in the present instance actually occurs (the top wall of the shell being bulged upwardly slightly), said dotted line representing the curvature of the exposed face of the disk on a diameter thereof.

Having thus fully described our inven-

tion, what we claim as new and desire to secure by Letters Patent is:—

1. The method of forming a bottle-cap as a completed article of manufacture which consists in placing a sealing disk in flatwise relation to a shell and then displacing the flange of the shell inwardly toward the central or vertical axis of the shell from different radial directions simultaneously and forcing it into permanent overlying relation to the margin of the disk, substantially as described.

2. The method of forming a bottle-cap as a completed article of manufacture which consists in placing a sealing disk in flatwise relation to a shell and then displacing the flange of the shell inwardly toward the central or vertical axis of the shell from different radial directions simultaneously and forcing it into permanent overlying relation to the margin of the disk, turning each portion of said marginal part affected by such displacement lever-fashion about a line of bending coinciding with an annular line surrounding said axis, substantially as described.

In testimony, that we claim the foregoing, we have hereunto set our hands this 9th day of December, 1910.

BENJAMIN ADRIANCE.
AMOS CALLESON.
